UNDERWATER GLIDER

Franz M. Foster, 1055 Desoto Road, Sarasota, Fla.

Filed Nov. 23, 1959, Ser. No. 58,439

Term of patent 14 years

(Cl. D71—1)

Fig. 1 is a bottom perspective view of an underwater glider showing my new design;

Fig. 2 is a top plan view;

Fig. 3 is an end view;

Fig. 4 is a bottom plan view; and

Fig. 5 is a partial rear view. The lines shown on the handles represent grooves.

I claim:

The ornamental design for an underwater glider, as shown and described.
